UNITED STATES PATENT OFFICE.

CHARLES HANSON VAN EPPS, OF SCOTT, INDIANA.

FENCE-WRENCH.

SPECIFICATION forming part of Letters Patent No. 448,564, dated March 17, 1891.

Application filed September 15, 1890. Serial No. 365,033. (No model.)

To all whom it may concern:

Be it known that I, CHARLES HANSON VAN EPPS, a citizen of the United States, and a resident of Scott, in the county of La Grange, 5 and State of Indiana, have invented certain new and useful Improvements in Fence-Wrenches; and I do hereby declare that the following is a full, clear, and exact description of the invention, which will enable others 10 skilled in the art to which it appertains to make and use the same, reference being had to the accompanying drawings, which form a part of this specification.

My invention relates to improvements in 15 locks for the fence wrenches or crossers by which the wires are crossed in building picket or paling fences.

The object of the invention is to provide 20 simple and economical means for locking or securing the wires of picket fences, thus enabling the pickets to be driven between the wires without liability of turning the crossers or wrenches and forcing the wires out of a horizontal position, thereby obviating the in- 25 convenience of holding the wrenches by hand.

The invention consists in the novel construction and combination of parts herein- 30 after fully described and claimed.

In the accompanying drawings, Figure 1 is 35 a perspective view of a portion of a wire picket fence and the wrenches or crossers with my improvement applied thereto. Fig. 2 is a vertical cross-section of the beam carrying the wrenches. Fig. 3 is a detail view of the beam and arms with the vertical bar removed.

In the said drawings, the reference-numeral 40 1 denotes the fence-posts set in the ground at suitable intervals in any well-known manner.

To the end post is secured one end of the wires 2 2^a, which wires are tightly stretched between the fence-posts and are secured to reels or other carrying devices in any ordinary manner.

The numeral 3 designates a vertical beam, 45 which has secured therein at the top, center, and bottom the arms or bolts 4, said arms projecting at right angles to said beam. The projecting portions of the right-angular ex- 50 tending arms or bolts are bifurcated and provided with perforations, through which pass

bolts, so as to permit of the wrench-plates 5 being pivotally secured therebetween. The edges of these plates adjacent to the pivotal points of the plates are provided with inclined slots 6 to receive the wires 2.

The inner face of the beam 3 is provided with a series of notches or depressions 3^a to receive the upper and lower edges of the triangular wrench-plates when raised or lowered. 60 The beam 3 is also provided upon one side with a series of inwardly-projecting bifurcated arms 7, to which is secured by means of bolts or pins passing therethrough a vertical bar 8, which is in a different vertical 65 plane from said wrenches, so as not to interfere therewith. This bar 8 is provided with a series of hooks 9 and 10, which alternately engage with the wires and hold them in place.

The numeral 12 designates a handle for 70 operating the beam.

The operation will be readily understood. When in the position shown in Fig. 1, the hooks 9 on the bar 8 engage with the near or inner wires 2 and prevent the crossers or 75 wrenches from being turned and the wires from being forced out of a horizontal position by inserting a picket between the wires. When it is desired to reverse the twisting- 80 plates to cross the wires, the beam 3 is elevated by the handle 12, causing the hooks 9 on the bar 8 to be disengaged from the wires, the wrenches to be reversed, and the wires crossed. The hooks 10 will then engage with the other wires 2^a.

Having thus described my invention, what I claim is—

In a picket-fence wrench or crosser, the combination, with the twisting-plates thereof and the beam to which said plates are pivoted, of a vertical bar secured to arms, projecting inwardly from said beam, and having hooks adapted to engage with the wires of the fence and hold them in position, substantially as described.

In testimony that I claim the foregoing as my own I have hereunto affixed my signature in presence of two witnesses.

CHARLES HANSON VAN EPPS.

Witnesses:

ADAM WILBER,
JOHN S. FLANDERS.
